REEL COVER

Samuel E. Brillhart, Lutherville, Md., assignor to
Western Electric Company, Incorporated, New
York, N. Y., a corporation of New York

Application November 30, 1946, Serial No. 713,245

7 Claims. (Cl. 206—59)

1

This invention relates to reel covers and more particularly to flexible removable covers for cable reels.

During the manufacture of coaxial cable, certain method steps are performed by the aid of one machine after which the partially completed cable is wound upon a reel and transported thereby to one or more additional machines employed for the completion of the cable. While the reels are transported from one machine to another, or temporarily stored between machine operations, it is important that the partially completed cables be completely enclosed in their reels.

An object of the invention is to provide a flexible cover for a reel which may be readily mounted on a reel to close the reel and is readily removable therefrom.

With this and other objects in view, the invention comprises a cover for a reel having spaced heads, the cover comprising members having bent side edges for interconnection with each other forming a flexible assembly of the members of sufficient length to extend around the reel.

More specifically the cover is formed of sheet metal members with their edges bent for interfitting hinge-like connections with each other to form an assembly of a length sufficient to surround a reel. Supporting elements are mounted upon the ends of the members to engage the heads of the reel and to support the reel when it is rolled from one position to another. Projecting lugs are formed integral with the supporting elements of one of the members disposed adjacent one end of the assembly, while flexible clamps are mounted upon the supporting elements of the member at the opposite end of the assembly for connection with the lugs to removably secure the assembly or cover on the reel. The supporting elements of one or more of the members interposed between the lugs and the supporting connection for the clamps have projections integral therewith to be engaged by the clamps and to be held in place thereby. Furthermore, the leading end of the assembly has a tongue member to project beneath the last member of the assembly when placed about a reel to completely enclose the cable on the reel.

Other objects and advantages will be apparent from the following detailed description when considered in conjunction with the accompanying drawings, wherein

Fig. 1 is a fragmentary side elevational view of a portion of the cover, two of the members

2

of the cover together with the tongue member being shown in solid lines in closed position and in dot-dash lines in open position;

Fig. 2 is a fragmentary top plan view of the structure shown in Fig. 1;

Fig. 3 is a fragmentary plan view of the inside of the cover;

Fig. 4 is an enlarged fragmentary sectional view taken substantially along the line 4—4 of Fig. 3 except that in this figure portions of the heads of a reel are shown in dotted lines;

Fig. 5 is a fragmentary sectional view taken along the line 5—5 of Fig. 2; and

Fig. 6 is a perspective view of the cover on a reel.

Referring now to the drawings, the cover indicated generally at 10 is composed of a plurality of like members 11 of the cross-sectional contours shown in Fig. 5. The members 11 have small bent edges 12 at one side thereof and large bent edges 14 at the other side thereof for forming hinge-like connections between the members. As illustrated, the small bent edges of one member are receivable in the large bent edges of the adjacent member permitting the members pivotal or hinge-like movement about the centerlines of these bent edges to complete a flexible assembly of as many members 11 as may be desired to surround a reel, the heads 15 of which are illustrated in Fig. 4. A tongue member 16 is interconnected with the adjacent edge of the leading member 11, the free edge of the tongue member being bent back upon itself as illustrated at 17 in Fig. 1.

Pairs of supporting elements 19 are formed of heavier and more durable material than the material employed in the forming of the members 11 and are secured by suitable means such as rivets to the ends of their respective members 11. The members 11 are preferably formed of sheet metal, while the elements 19 are forged or otherwise formed to support the reel when it is rolled from one position to another. The ends of the elements 19 lie on the peripheries of the heads 15 while other elements 21, identical in structure to the elements 19 with the exception of their greater lengths (Fig. 3) and their inwardly extending flange portions 22, are positioned between pairs of the elements 19 to cooperate therewith in supporting the reel, the flange portions serving also to hold the cover in place on the reel. One pair of elements 21 has integral projecting lugs 23 in the form of hooks as illustrated in Figs. 1 and 2. The adjacent elements 21 have lateral projections 24 integral

therewith recessed at 25 in their upper surfaces to receive springs 26 of clamps indicated generally at 27.

The springs 26 of the clamps 27 are connected to apertured flanges 28 integral with the elements 21 of the last member 11 of the assembly. The free ends of the springs 26 are secured by the aid of rivet-like members 29 to brackets 30. A pin 31 supported by the bracket 30 serves as a pivot for a lever 32. U-shaped catches 33 are formed to engage the lugs 23, the legs of the catches being pivotally connected at 35 to their respective levers 32. The levers 32 are hollow or substantially U-shaped in cross-section throughout the major portion of their lengths to extend over, not only their brackets 30, but the adjacent portions of their springs 26. The free ends of the levers 32 are bent outwardly at 36 so that the operator may readily grip the lever to actuate it.

The cover may be readily placed about the reel whether the reel is supported in its take-up position in a machine, or resting upon the floor or other suitable support. If the reel has completed its service as a take-up reel, and it is desirable to cover the reel and enclose the complete or partially formed cable prior to its removal from the machine, the cover may be placed upon the reel and the ends of the covers brought together beneath or near the end of the machine with the clamps 27 in open position so that the catches 33 may be readily moved into engagement with the hook shaped lugs 23. At this time, with the latches in open position, the levers 32 extend to the right of their pivots 31. The operator, prior to connecting the latches and during the positioning of the cover on the reel, guides the tongue member 16 at the leading end of the cover beneath the rearmost member 11 to completely cover the reel and enclose the cable. The clamps 27 may then be closed by moving the levers 32 about their pivots 31 to the position shown in Figs. 1 and 2. During this movement of the levers the springs 26 will be expanded, establishing a pulling force therein which is sufficient to hold the cover tightly on the reel. It will be noted that when the clamps are in their closed positions the pivots 35 for the catches 33 and the connection of the catches with the lug 23 will lie in planes beyond the center-lines of their respective pivots 31. To place the cover on the reel when the reel is resting on the floor, the cover is placed on the floor in the position shown in Fig. 3, and the reel rolled on to the cover to approximately the center thereof. The ends of the cover are brought into overlapping positions and the clamps connected to their lugs and closed as previously described.

The cover may be readily removed from the reel by moving the levers 32 into open position to release the forces of the springs 26 and free the catches 33 for removal from their lugs 23, the cover then being free to be removed from the reel. The formation of the members 11 not only completely enclose the reel, through the assistance of their elements 19 and 21, but provide a flexible structure conformable to reels of varied diameters. The members 11 being constructed of sheet metal are light in weight and sufficiently durable, the major wear on the cover being concentrated on the elements 19 and 21 which are heavier structures and support the reel while being transported or rolled from one position to another.

Another important feature of the reel cover lies in the function of the clamps 27 to loosen the cover sufficiently for the opening of a door portion thereof and at the same time hold the re-

maining portion of the cover about the reel. The door portion is composed of the tongue member 16 and its two immediately connected members 11. When the clamps are in their closed positions the door portion is held closed, but when the levers 32 of the clamps are swung clockwise (Fig. 1) about their pivots 31 the ends of the cover are free to move away from each other to free the tongue 16 and allow the door portion to be opened. When the door portion is open, as illustrated in dot-dash lines in Fig. 1, the cable may be tested by connecting it to a test set. The cover, when initially placed on the reel, has its door portion adjacent the end of the cable. After the desired tests have been completed the end of the cable may be disconnected from the test set, positioned beneath the cover, the door portion closed and the levers 32 of the clamps moved into their closed positions.

Although specific improvements of the invention have been shown and described, it will be understood that they are but illustrative and that various modifications may be made therein without departing from the scope and spirit of this invention as defined by the appended claims.

What is claimed is:

1. A cover for a reel having spaced heads, the cover comprising members having bent side edges for forming a hinge-like interconnection with each other forming a flexible assembly of the members of sufficient length to extend around the reel, projecting lugs mounted on one of the members near one end of the assembly, and flexible clamps mounted on the member at the other end of the assembly for connection with the lugs to removably secure the assembly on the reel.

2. A cover for a reel having spaced heads, the cover comprising members having bent side edges for forming a hinge-like interconnection with each other forming a flexible assembly of the members of sufficient length to extend around the reel, supporting elements mounted upon the ends of the members to engage the heads of the reel, projecting lugs integral with the supporting elements of one of the members disposed adjacent one end of the assembly, and flexible clamps mounted on the supporting elements of a member adjacent the other end of the assembly for connection with the lugs to removably secure the assembly on the reel.

3. A cover for a reel having spaced heads, the cover comprising members having bent side edges for forming a hinge-like interconnection with each other forming a flexible assembly of the members of sufficient length to extend around the reel, a tongue member, having one edge hingedly connected to the adjacent edge of the first member in the assembly, to partially extend beneath the last member in the assembly when the assembly is positioned about the reel, and means carried by one end of the assembly to removably secure the assembly on the reel.

4. A cover for a reel having spaced heads, the cover comprising members having bent side edges for forming a hinge-like interconnection with each other forming a flexible assembly of the members of sufficient length to extend around the reel, projecting lugs mounted on one of the members near one end of the assembly, flexible clamps mounted on the member at the other end of the assembly for connection with the lugs to removably secure the assembly on the reel, and projections integral with a member intermediate the members supporting the clamps and the

lugs to be engaged by the clamps and held in place thereby.

5. A cover for a reel having spaced heads, the cover comprising laterally extending members hingedly connected to each other forming a flexible assembly of the members of sufficient length to extend around the reel, certain of the members at one end of the assembly forming a door portion, and a clamping unit actuatable into closed position, to secure the assembly on the reel to close the space between the heads of the reel, and actuatable into open position to free the door portion for movement into open position while maintaining the remainder of the assembly about the reel.

6. A cover for a reel having spaced heads, the cover comprising laterally extending members hingedly connected to each other forming a flexible assembly of the members of sufficient length to extend around the reel, certain of the members at one end of the assembly forming a door portion, and clamping units, carried by a member adjacent one end of the assembly for removable connection with a member adjacent the door portion, actuatable into closed positions to secure the assembly on the reel with the door portion closed completely enclosing the space between the heads of the reel, and actuatable into open positions to free the door portion for movement into open position while maintaining the remainder of the assembly about the reel.

7. A cover for a reel having spaced heads, the cover comprising members formed of sheet material with their side edges bent to form interfitting hinge-like connections between successive members to complete a flexible assembly of the members of sufficient length to extend around the reel, supporting elements secured to the ends of the members to engage the peripheries of the reel heads and extend outwardly beyond the members when positioned on a reel to act as the supports for the reel, projecting lugs integral with the supporting elements of one of the members adjacent one end of the assembly, and flexible clamps mounted on the other end of the assembly for connection with the lugs to removably secure the assembly on the reel.
